FOREIGN PATENT DOCUMENTS

WO WO2007122304 11/2007

Primary Examiner — Kelley A Donnelly(74) *Attorney, Agent, or Firm* — MALLOY & MALLOY, P.L.(57) **CLAIM**

The ornamental design for a display case, as shown and described.

DESCRIPTION

FIG. 1 is a front view illustrating my design for a display case;

FIG. 2 is a left side view thereof, the right side being a mirror image;

FIG. 3 is a top view thereof;

FIG. 4 is a front perspective view thereof; and,

FIG. 5 is a left side section view thereof, along line 5-5 of FIG. 1.

The broken lines in the drawings are included for purposes of illustrating portions of the display case that form no part of the claimed design.
